UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

LOOM.

Original application filed February 18, 1925, Serial No. 9,958. Divided and this application filed May 28, 1927. Serial No. 194,870.

This invention relates to looms; more particularly to looms for weaving relatively heavy stiff strand material, such, for example, as may be made from strips of paper formed into cord or twine, this application covering subject matter divided out from my application Serial No. 9,958 filed February 18, 1925 for looms and relating more particularly to means for cutting off the picks and holding them in proper position in the fabric. For a more complete understanding of this invention reference may be had to the accompanying drawings in which

Figure 1 is a right end elevation of the loom.

Figure 2 is a detail in perspective showing means for holding one end of the pick in the fabric.

Figure 3 is a transverse section parallel to Figure 1 through an intermediate portion of the loom.

Referring to these figures, each warp strand passes about a tension device indicated generally at A, through a shedding mechanism indicated at B, and through a filling laying mechanism at C, where the filling strands are woven to form with the warp strands the desired fabric. The detail constructions of these various mechanisms is fully described in the parent application hereinbefore referred to and will not be described herein, except in so far as it may be necessary or desirable to afford a clearer understanding of the subject matter herein presented and claimed.

The shedding mechanism comprises the harness frames 40 and 41 which are moved up and down by eccentric straps 48 on eccentrics fixed to the shaft 49. Preferably the harness frames are arranged in two pairs positioned end to end and moved out of time with each other, as disclosed in the parent application hereinbefore referred to, to produce progressive shedding between the center and sides of the fabric.

A filling laying mechanism C comprises a lay 60 having a reed 61 extending thereacross at its upper end. Fixed to the reed is a pair of slotted plates 65 shaped to define with the reed a substantially channel-shaped guide-way 67 for the passage of a pick-laying member carrying a suitable strand gripping device extending outwardly between the adjacent edges of the plates 65.

After each pick strand has been laid the lay is given a forward motion in order that the reed may beat up this strand against the fabric already woven. For this purpose the lay is mounted on a slideway 120 at each end, and has fixed thereto at each end and at intermediate points, if desired, the forward ends of links 121. The rear end of each link 121 carries a cam follower 122 which engages a cam slot 123 in a cam member 124 which may be fixed to one face of a gear 125. In order to hold the cam followers 122 in proper position relative to the cams, the rear ends of the links 121 are suspended on link hangers 135, each of which is pivoted as on a stub shaft 136 projecting from one face of a bracket 137 fixed to the machine. The shaft 49 actuating the harness frames is also driven from the shaft 127 as by intermeshing gears 140 and 141 fixed on these respective shafts. As shown each of the gears 125 is fixed to a shaft and meshes with a gear 126 carried by a main shaft 127 extending across the machine. As shown best in Figure 1, one end of the shaft 127 may have fixed thereon a worm wheel 128 with which engages a worm 129 carried by a jack shaft 130. This jack shaft may be coupled, as by means of a sliding clutch 131, to the shaft 132 of a driving motor 133. The cams 124 are so formed that forward and backward motions of the lay to beat up the pick and then retract in position to lay succeeding picks through the shed are effected in suitable timed relation to the remaining operations of the machine.

As each strand is being beaten up by the forward movement of the lay, it is cut off at the side of the fabric from which it was drawn in. This cutting mechanism comprises a pair of blades 165 and 166. The blade 165 is mounted in fixed position while the blade 166 is pivoted at 167 thereto. This blade 166 has extending from its lower portion a finger 168 which is positioned in the path of movement of the link 121 in such a manner that as the lay moves forwardly at each beating up motion it strikes the finger 168 and rocks the blade 166 downwardly, bringing its cutting edge 169 into shearing relation with an edge 170 of the fixed blade between which the filling strand is carried as the lay moves forwardly. When the blade 166 is in closed position with

the blade 165, the strand has been engaged therebetween and cut off on the side of the fabric from which it was drawn into the shed. A spring 171 extending from a lug 172 at the forward end of the movable blade 166 and hooked into a lug 173 carried by a fixed frame member acts to hold the pivoted blade normally out of operative relation until it is forced into its cutting position 10 by impingement of the lay on the finger 171.

After the gripper has released the end of the pick strand which it has previously laid and this strand has been beaten into position, this cut end might tend to unravel 15 from the warp strands before the laying of the succeeding pick. In order to prevent such an occurrence a retaining hook 180 shown in detail in Figure 2 has been provided. This hook has a downwardly turned 20 extremity 181 adapted to engage back of the last laid pick after it has been beaten up into position, this pick being indicated at *b*. This hook is pivoted at 182 to a fixed portion of the machine and is provided with a laterally extending pin 183. Extending 25 forwardly from the lay in alignment with this hook 180, as best shown in Figure 1, is a cam element 184 having a cam block 185. This block when the lay is in its forward position rides beneath the pin 183 of the hook and raises it, causing the hook to rock about its pivot 182, thus raising its 30 extremity 181 from back of the strand *b* so as to permit a succeeding pick which is being beaten up in this forward motion of the lay to be placed in position to be engaged by the extremity 181 when the retraction of the lay permits this end to fall by its own weight into position back of the 35 pick.

As shown in Figure 2, one or more fabric strands *c* are used as the extreme warp strands from which the fabric is made and

the hook is positioned to engage the pick between this marginal warp or warps and 45 those in the main body of the fabric. These marginal strand or strands are used to effect a tying of the ends of the picks in position these warp strands holding more tightly to the picks than do the warp strands of 50 paper from which the body of the fabric is formed.

Having thus described an embodiment of this invention, it should be evident to those skilled in the art that various changes and 55 modifications might be made therein without departing from its spirit or scope as defined by the appended claims.

I claim:

1. In combination with a reed, means for 60 laying individual picks of strand material, and means for moving said reed to beat up each pick as laid, of a member normally biased to engage the last pick adjacent to one end after each beating operation to retain said end from unraveling, and means actuated by the movement of said reed at each beating movement for removing said member to permit a succeeding pick beaten up to be presented in position to be engaged 70 thereby.

2. In combination with a reed, means for laying individual picks, and means for moving said reed to beat up the picks, of a hook normally biased to engage back of each pick 75 adjacent to one end after it has been beaten up and serving to prevent unraveling thereof, and an element movable with said reed and engaging and removing said hook from its biased position during the beating movement, to permit a succeeding pick to be brought into position to be engaged by said hook.

In testimony whereof I have affixed my signature.

EARL F. BALDWIN.
